(57) **CLAIM**

The ornamental design for a mounting bracket, as shown and described.

DESCRIPTION

FIG. 1 is a top perspective view of a mounting bracket illustrating our new design;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

Dashed lines in the drawings illustrate unclaimed portions of the mounting bracket that form no part of the claimed design.

As indicated in the title, the article of manufacture to which the ornamental design has been applied is a mounting bracket. As non-limiting examples, such mounting brackets can be found integrated in and/or otherwise coupled to vehicles, industrial machinery, commercial equipment and/or consumer products, such as a gas spring mounting bracket, for example.
